INVENTOR,

Morgan S. Clark,
by Louis Dagger, Esq.
Attorney.

UNITED STATES PATENT OFFICE.

MORGAN S. CLARK, OF TORONTO, KANSAS.

COMBINED SHEARS, BUTTON-HOLE CUTTER, AND RIPPER.

SPECIFICATION forming part of Letters Patent No. 404,169, dated May 28, 1889.

Application filed September 22, 1888. Serial No. 286,061. (No model.)

To all whom it may concern:

Be it known that I, MORGAN S. CLARK, a citizen of the United States, and a resident of Toronto, in the county of Woodson and State 5 of Kansas, have invented certain new and useful Improvements in a Combined Ripper, Button-Hole Cutter, and Shears; and I do hereby declare that the following is a full, clear, and exact description of the invention, 10 which will enable others skilled in the art to which it appertains to make and use the same.

This invention relates to a combined ripper, button-hole cutter, and shears.

The object is to produce a device which 15 shall be of such construction that it may may be used as a ripper, button-hole cutter, and shears; furthermore, to produce a device which shall be simple of construction, efficient and durable in use, and comparatively inexpensive of production.

With these objects in view the invention 20 consists in the improved construction and combination of parts of a combined ripper, button-hole cutter, and shears, as will be hereinafter fully described in the specification, 25 illustrated in the drawings, and pointed out in the claims.

In the accompanying drawings, forming 30 part of this specification, and in which like letters of reference indicate corresponding parts, Figure 1 is an elevation of my improved shears, showing the ripper closed or pushed back out of the way. Fig. 2 is a similar view showing the ripper pushed out and ready for 35 use. Fig. 3 is an edge view of a portion of the blade carrying the ripper. Fig. 4 is a side elevation of a portion of the blade, showing the ripper removed; and Fig. 5 is a detail view of the ripper.

Referring to the drawings, A designates the 40 shears, consisting of two blades, 1 and 2, which are of the ordinary construction. The handles 3 are provided, as will be seen, on their inner edges with cutting-edges 4 and 5, which 45 form the button-hole-cutting portion of the device.

B designates the ripper, to be used when it 50 is desired to rip a seam that has been sewed.

This ripper, as will be observed, is provided 55 with inclined edges or faces 6, which fit

in a dovetailed recess, 7, in the blade 2, and is of such a width that when pushed in, as shown at Fig. 1, it will be level with the edge of the blade, and when pulled out will project a sufficient distance beyond the edge of 55 the blade to allow it to perform the function for which it is designed. This ripper may be held in place in any desired manner; but that shown in the drawings is preferred, which consists of a flat spring, 8, which bears against 60 the under side of the ripper, thus holding it in the desired position.

In order to regulate the desired size of the button-holes to be cut, a set-screw, 10, is placed 65 in the handle of the blade 2, and rests against the shoulder 11 of the blade 1 when the blades are brought together. Thus it will be seen that by simply turning the set-screw the length of the hole to be cut may be regulated 70 at will.

The advantage of having the button-hole 75 cutter on the handle of the shears instead of on the blade will be obvious, for two reasons: The first one is that it will prevent the necessity of cutting a recess in the blades, which has to be done with the ordinary button-hole 80 cutter; and, in the second place, a much more powerful leverage can be obtained by having them at the rear part of the shears and behind the pivot instead of in front of it.

It will thus be seen that, although this device is exceedingly simple of construction, it 85 will be found highly efficient and durable in use, and may be constructed at but a slight expense.

Having thus fully described my invention, what I claim as new, and desire to secure by Letters Patent, is—

1. The combination, with one of the blades 90 of the shears, having at its rear end a cutting-edge to be used in cutting button-holes, and a set-screw for regulating the size of the same, of a dovetailed recess formed on its outer side, designed for the reception of a ripper, substantially as described.

2. The combination, with one of the blades 95 of a pair of shears, having at its rear end a cutting-edge formed for cutting button-holes, a set-screw engaging an opening in the said handle and designed to regulate the size of 100

the holes to be cut, a dovetailed recess formed on the said blade, and a ripper provided with a cutting-edge and having its sides beveled to engage the said recessed opening, substantially as described.

3. The combination, with the ripper mounted in a dovetailed recess formed in the upper edge of one of the blades, of a spring secured within the said recess and adapted to

hold the ripper in any desired position, substantially as described.

In testimony that I claim the foregoing as my own I have hereunto affixed my signature in presence of two witnesses.

MORGAN S. CLARK.
